OIL BURNER

Howard L. Stolper, Burbank, and Henry H. Moreton, Laguna Beach, Calif.

Application August 27, 1937, Serial No. 161,320

2 Claims. (Cl. 158—77)

This invention is an oil burner designed to effect maximum consumption of a combustible mixture produced during its operation.

One of the objects of the invention is to provide a simple and efficient method of producing a uniform and highly combustible mixture of hydrocarbon and air or gas. A further object is to provide simple means for converting hydrocarbon oil into a spray, by atomization prior to mixing the same with air or other gas. A further object is to provide means for insuring positive and even feed of the hydrocarbon liquid to a spraying nozzle. A further object is to provide means for eliminating what is known as the "black spot" in the flame of a burner. A further object is to provide a mechanism that will atomize oil or other liquids and mix the atomized liquid with air or other gases in such manner as to derive the highest efficiency in the consumption of the mixture.

The invention will be hereinafter fully set forth and particularly pointed out in the claims.

In the accompanying drawing:

Figure 1 is a side elevation partly in section illustrating a burner constructed in accordance with the invention. Figure 2 is an enlarged end view of the pump mechanism. Figures 3 and 4 are detail views illustrating the spray nozzle.

Referring to the drawing, 10 designates an electric motor of any preferred construction, supported upon a suitable base and provided with the usual armature shaft 11.

Mounted on the shaft 11 so as to rotate therewith, is the driving-gear-impeller member 13 of a gear pump P, said gear impeller member being mounted within a suitable pump casing located adjacent to the motor. The gear impeller member 13 meshes with a smaller driven-gear-impeller member 14 within the pump casing, and the latter is provided with an inlet port 15 and an outlet port 16. The inlet opening 15 is connected with a source of fuel supply (not shown) by a conduit 15a.

The pump gear impeller member 14 is mounted upon a tubular shaft 17 in such manner as to rotate therewith, and so that the shaft 17 may be driven by the said member 14. Said tubular shaft 17 is rotatably mounted in bearing 18 formed on the pump casing and a bearing 19 resting upon the base 20 which also supports the pump casing. It will be noted that the gear-impeller members 13 and 14 are of different diameters, so as to increase the number of rotations of the smaller gear impeller member, although the peripheral speed of the two gears will remain

the same, whereby the pumping functions are in no way impaired.

It will be noted that the shaft 17 is provided with a longitudinal bore 25, and that the rear end of said shaft, i. e. the left end as illustrated in Figure 1, is enclosed by a casing 22, removably secured to the pump casing, and provided with an oil inlet opening 23, which is connected with the outlet opening 16 of the pump by means of a conduit 16a. The rear end of the shaft 17 extends into the chamber 22 in such manner that fuel oil forced by the pump through the conduit 16a will enter and flow through the chamber 22, and into the rear end of the bore 25. The fuel intake pipe 15a is connected by means of a bypass conduit 24 with the chamber 22, so that any excess fuel oil will circulate through the chamber 22 and back to the fuel inlet pipe 15a.

The motor 10 is connected with a suitable source of electrical energy (not shown) in any well known manner, and its operation controlled by suitable rheostats which it is deemed unnecessary to illustrate. Located above the motor is a transformer T, which is connected by suitable electrical leads 26, with one or more electrical ignition devices 27, which extend into the combustion chamber C.

The shaft 17 is provided with an axial extension 17a, the outer free end of which is located within the combustion chamber C, at a position adjacent to the ignition devices 27. The outer free end of the conduit extension is covered by a closure member secured thereto in suitable manner, said closure member having a wall which extends across the open end of the conduit. Said wall is provided with a minute discharge orifice which is radially spaced from the normal axial center of the bore 25, and located at such a position that a gyroscopic movement will be imparted to the liquid discharged through the orifice during rotation of the conduit, said gyroscopic effect being obtained by reason of the orbital travel of the orifice around said axial center.

Mounted upon the shaft 17 by means of a suitable hub 30a is a fan 30, which is located within a blower casing 31, and provided with vanes 32 arranged parallel with the axis of the shaft 17, but of concavo-convex form and so arranged as to draw atmospheric air through the inlet opening 33 and to propel it through the air supply casing 31. The diameter of the blower 32 is greater than the diameter of the driven gear 14, and therefore the peripheral speed of the fan will be correspondingly greater than the peripheral speed of the gears, whereby air is supplied from

the blower to the mixing means faster than the hydrocarbon liquid is supplied to said mixing means, so that the desired proportions of air and hydrocarbon are maintained. Said casing is provided with a channel of annular cross section and increasing diameter, produced by a conically shaped interior wall 34. The air is directed through a pipe 35 into the mixing chamber M, said pipe being of smaller diameter than said mixing chamber so as to provide a surrounding annular space 36, through which additional atmospheric air may enter said chamber. The mixing chamber M discharges into a combustion chamber C, which is lined in suitable manner.

The heat produced by the combustion may be utilized in any desired manner. In operation, the motor 10 causes a rotation of the shaft and its extension 17*, and with it a concurrent rotation of the gear-impeller member 14. As the pump P operates the oil or other liquid is delivered to the chamber 22, and from thence is forced into the rear open end of the bore 25. The structure of the pump is such that a uniform pressure is maintained upon the oil as it flows through the bore and is discharged through the opening in the nozzle 28. The arrangement of the gears 13 and 14 is such as to increase the number of revolutions per minute of shaft 17 as compared to those of shaft 11. The high speed rotation of the shaft 17 and its extension 17*, together with the offset position of the discharge opening 29 of the nozzle 28 serves to scatter the atomized liquid by a gyratory motion. Simultaneously with the discharge of atomized oil into the mixing chamber, atmospheric air is forced into said chamber by the fan 30, said air entering through the air inlet opening 33, and being delivered into the mixing chamber M, together with additional air which is sucked in through the opening 36, so that when the mixture is brought into contact with the incandescent ignition device 27, practically complete combustion is accomplished. The operation of the device produces a rotating or gyratory flame, which does not fan out, and mixing of the fuel with the air driven through the mixing chamber is much more complete and effective than is possible by means of a fixed nozzle. In other words, although the orifice of the nozzle is in an approximately fixed position, the discharge therefrom is of a gyratory nature. Thus, it is possible to produce a flame of extreme length but of small diameter. Obviously, the distance and direction off-center of the orifice and the longitudinal bore, are important factors in controlling the outside diameter of the flame.

An important advantage of the invention is that in operation there is no impinging of raw vapor on the sides of the fire chamber, so that formation of carbon through the chilling of the

fuel stream is prevented. The arrangement also is such that the walls of the fire chamber become and remain red hot, and the reflected heat produces a more combustible mixture than would be possible if the vapor is allowed to impinge on the sides of the fire chamber. If desired, the operation may be controlled in a well known manner through the medium of thermostatic devices which are so well known in the art that illustration thereof is deemed unnecessary. An important advantage is that the ratio of the gears of the pump may be so designed as to impart a desired speed of rotation to the blower so as to adequately supply the volume of air required for perfect combustion.

Having thus explained the nature of the invention and described an operative manner of constructing and using the same, although without attempting to set forth all of the forms in which it may be made, or all of the forms of its use, what is claimed is:

1. An oil burner comprising a rotatively mounted tubular shaft having a receiving end and a delivery end, a discharge nozzle on said delivery end, a gear pump having two intermeshing gear-impeller members of different diameters, the gear-impeller member of smaller diameter being secured to said shaft, a supply pipe connecting the delivery side of said pump to the receiving end of said shaft, power means operating independently of the tubular shaft for rotating the larger driving-gear-impeller member, whereby oil is fed to the tubular shaft simultaneously with the rotation of the latter, and a fan secured to and rotatable with said shaft at a position between the pump and the nozzle.

2. An oil burner comprising a rotatively mounted tubular shaft having a receiving end and a delivery end, a nozzle on said delivery end having a single discharge orifice spaced radially with respect to the axis of the shaft, a gear pump including a casing and two intermeshing gear-impeller members of different diameters, the smaller gear-impeller member being secured to said shaft so as to rotate therewith, a bearing for the inlet end of the shaft extending from said pump casing, an oil delivery casing supported by said casing and connected with the inlet end of the conduit, means connecting the pump casing with said oil delivery casing, power means operative independently of the tubular shaft for rotating the larger gear-impeller member, whereby oil is fed to the tubular shaft simultaneously with the rotation of the latter, and a fan secured to and rotatable with said shaft at a position between the pump and the nozzle.
